UNITED STATES PATENT OFFICE.

JOHN PETRO, OF WATERBURY, CONNECTICUT.

WINDOW-SCREEN.

1,274,768.

Specification of Letters Patent. Patented Aug. 6, 1918.

Application filed September 12, 1916. Serial No. 119,705.

To all whom it may concern:

Be it known that I, JOHN PETRO, a citizen of the United States, residing at Waterbury, in the county of New Haven, State of Connecticut, have invented certain new and useful Improvements in Window-Screens; and I do hereby declare the following to be a full, clear, and exact description of the invention, such as will enable others skilled in the art to which it appertains to make and use the same.

The present invention is directed to improvements in window screens, and has for its object to provide a device of this character 15 acter so constructed that it can be rolled when not in use and readily unrolled for use.

A further object of the invention is to provide a window screen of this character 20 so arranged that when unrolled it will cover the entire window openings so that both the upper and lower sashes can be opened.

A still further object of the invention is to provide a window screen of this nature 25 having a roller which is controlled by a spring mounted adjacent the roller so that should the spring break or get out of order it can be replaced or repaired.

Still another object of the invention is to 30 provide a window screen which can be readily attached to the window frame, and when not in use can be rolled and retained within a casing at the top of the window frame and out of the way.

With these and other objects in view this 35 invention resides in the novel features of construction, formation, combination and arrangement of parts to be hereinafter more fully described, claimed and illustrated in 40 the accompanying drawing in which:—

Figure 1 is a front view of a window casing showing the device in place.

Fig. 2 is a sectional view on line 2—2 of Fig. 1.

Fig. 3 is a sectional view on line 3—3 of Fig. 1.

Fig. 4 is a sectional view on line 4—4 of Fig. 1.

Referring to the drawing 1 indicates the 50 plate which is adapted to be secured to the top bar of the window frame, said plate having mounted thereon brackets 2 and 3, the latter having bearings 4 and 5 formed therein, while the former has a bearing 6.

55 A roller 7 is employed and has its trunnion 8 engaged in the bearing 6 of its trunnion

9 engaged in the bearing 5. Fixed to the trunnion 9 is a gear 10 which is in mesh with the pinion 11 fixed to the shaft 12, said shaft having one end engaged in the bearing 4 and its other end engaged in the bearing 13 carried by the bracket 14, said bracket being mounted on the plate 1. Encircling the shaft 12 and having one end connected to the bracket 14 is a coil spring 15, the other 60 end of which is fixed to the shaft 12 adjacent the outer end thereof.

Windable on the roller 7 is a screen 16 which has its lower edge engaged in the recess 17 carried by the strip 18, said screen 70 being secured in the recess by a strip 19.

Secured on the plate 1 adjacent the side edge of the screen 16 are arms 20 said arms having their lower ends provided with bearings 21 for rotatably supporting the roller 75 22, said roller being held against accidental disengagement from the bearings 21 by angle brackets 23, which are secured to the lower edge of the plate 1 and adjacent the ends of said roller.

The plate 1 is provided with a recess 24 in which is engaged the screen 16, said screen being engaged with the roller 22 which permits the free movement of the screen and will thus hold the strip 18 alined 85 with the plate 1.

Hooks 25 are pivotally connected to the strip 18 and are adapted to engage the screw eyes 26 which are secured to the window sill 27. In some instances it is necessary to use 90 the plates 28 which are pivotally connected to the strip and are provided with key hole slots 29 for engaging the studs 30 which are carried by the sill 27. In any event the hooks 25 and plates 28 when engaged with 95 their respective securing device will serve to hold the lower edge of the strip 18 engaged with the upper surface of the sill 27, and at which time the spring 15 will be under tension since when the screen is lowered the 100 roller will be rotated and rotary movement transmitted to the shaft 12 through the medium of the pinions 10 and 11. Thus it will be seen that upon releasing the hooks 25 or plates 28 that the screen 16 will rewind upon 105 the roller 7.

Engaged with the plate 1 are arms 30' which serve to support a curtain pole, when desired, said arms being located upon opposite sides of the casing 31, said casing serving to inclose the roller 6 and adjacent parts 110 so that when the screen 16 is not in use and

is wound upon the roller the entire device will be out of sight, but ready for use when desired.

Mounted on the plate 1 are plates 32, said plates having adjustably connected thereto shade supporting brackets 33, which can be adjusted longitudinally for supporting shade rollers of different lengths.

From the foregoing description it will be seen that should the spring 15 become worn or broken it can be conveniently repaired or a new one substituted since the same is mounted independently of the roller 7. It is obvious that when the strip 18 is engaged with the sill 29 the screen 16 will close the window opening.

What is claimed is:—

A device of the character described comprising a plate having a recess in its bottom,

a roller supported by the plate and spaced laterally therefrom, a spring actuated shaft supported by the plate adjacent the roller, gearing connecting said shaft with said roller, a second roller disposed beneath said plate and in vertical alinement therewith, and a screen wound on the first named roller and engageable around the second named roller whereby a portion of the screen is disposed in said recess and the portion thereof below said second named roller maintained in vertical alinement with said plate.

In testimony whereof I affix my signature in the presence of two witnesses.

JOHN PETRO. [L.S.]
